UNITED STATES PATENT OFFICE.

ARTHUR L. HALLIDAY, OF NEW YORK, N. Y.

DESIGN FOR CARPET.

SPECIFICATION forming part of Design No. 27,083, dated May 18, 1897.

Application filed April 2, 1897. Serial No. 630,482. Term of patent 3½ years.

To all whom it may concern:

Be it known that I, ARTHUR L. HALLIDAY, a subject of Her Majesty the Queen of Great Britain, residing at the city of New York, in the county of New York and State of New York, have invented and produced a new and original Design for a Carpet or other Fabric, of which the following is a specification, reference being had more particularly to the accompanying drawing, illustrating the same and forming part hereof.

The leading feature of my design comprises a rococo pattern consisting of rococo ornaments and conventional flower and leaf forms.

15 In the drawing, *a* is the body, *b* the border, and *a b* the complete carpet.

c are the rococo ornaments.

d are the conventional flower and leaf forms.

The pattern is well spread over the ground 20 and is adapted for self-coloring—that is, for being expressed in different shades of one

color, which is also applied to the ground. However, the design of my invention will be best understood by reference to the accompanying drawing, and it may be expressed in 25 different colors or combinations of colors and applied to velvet, Wilton, Brussels, ingrain, and other carpets.

What I claim as my invention, and desire to secure by Letters Patent, is— 30

1. In a design for a carpet, the body *a*, substantially as shown.
2. In a design for a carpet, the border *b*, substantially as shown.
3. The design for a carpet consisting of the 35 body *a*, and border *b*, substantially as shown.

In testimony whereof I have hereunto signed my name.

ARTHUR L. HALLIDAY.

In presence of—

OWEN WARD,

JACOB KAUTZMANN, Jr.
